UNITED STATES PATENT OFFICE

115,851

DESIGN FOR AN AUTOMOBILE TIRE

Harry C. Hower, Chicago, Ill.

Application September 2, 1937, Serial No. 71,432

Term of patent 7 years

To all whom it may concern:

Be it known that I, Harry C. Hower, a citizen of the United States, residing at Chicago, in the county of Cook and State of Illinois, have invented a new, original, and ornamental Design for an Automobile Tire, of which the following is a specification, reference being had to the accompanying drawings, forming a part thereof.

In the drawings, Figure 1 is a perspective view, partially in dotted lines, of a tire showing my new design.

Figure 2 is a fragmentary sectional perspective view of the tire of Figure 1, taken substantially along the plane of line 2—2 thereof.

The tire having a tread face extending from side wall to side wall thereof and substantially entirely divided by a plurality of circumferential tread grooves into a plurality of relatively narrow continuous circumferential tread ribs, in conjunction with the centrally disposed tread rib of the plurality of tread ribs having laterally

aligned and circumferentially spaced projections extending laterally outwardly from opposite sides of the rib, each of the other ribs of the plurality of ribs having circumferentially spaced recesses extending laterally inwardly from one side thereof and circumferentially spaced projections extending laterally outwardly from the opposite side thereof, the recesses on the one side of said latter ribs being staggered with respect to the projections on the opposite side of said ribs, the recesses and projections on adjacent ribs being disposed in substantially interlocking engagement with respect to each other, and alternate ribs being provided with a plurality of relatively minute continuous beads extending circumferentially thereof, constitute the dominant features of my present design.

I claim:

The ornamental design for an automobile tire, as shown and described.

HARRY C. HOWER.
